D. J. GALLAGHER

FASTENER FOR WINDOWS, DOORS, AND THE LIKE

Filed July 8, 1927

Dennis Joseph Gallagher, Inventor
By: Fred Parker, Attorney

UNITED STATES PATENT OFFICE.

DENNIS JOSEPH GALLAGHER, OF BROOKLYN, NEW YORK.

FASTENER FOR WINDOWS, DOORS, AND THE LIKE.

Application filed July 8, 1927. Serial No. 204,194.

This invention relates to a fastening means for window sashes of various kinds, shutters, covers, or doors, or other closures, having a pair of associated members which it is desired to secure together, and many other structures having similar intermovable parts which need to be fastened together; as, for further example, dumb-waiter doors, and swinging or casement windows, and the like structures of many types and kinds.

The main object is to provide a fastener that is cheap and easily made and applied; and one which has a wide variety of uses and cannot be easily tampered with or improperly opened; and to this and other ends, the invention consists essentially in the construction, combination, and arrangement of parts, substantially as will be hereinafter described and claimed.

20 In the accompanying drawing illustrating my invention:

Figure 1 is a vertical cross-section of the meeting rails of an upper and lower window sash, with my improved fastening means applied thereto, the view being in section on the line 1, 1, of Figure 2.

Figure 2 is a top plan view of the same fastener shown in Figure 1, delineated as arranged with portions of the sash rails to 30 which the parts are secured.

Figure 3 is a detail cross-section on the line 3, 3, of Figure 1.

The upper and lower sashes 3 and 4 of a window are given merely as an example 35 of means with which my fastener may be used. I am not to be confined thereto.

I have therefore shown the lower rail 1 of the top sash 4, having a fragment of the window glass 1^a attached thereto, and upper rail 2 of the lower sash 3, having a fragment of the window pane 2^a fastened thereon; said rails 1 and 2 being the horizontal meeting rails of a window which are commonly provided with a fastener whose parts 45 may be interengaged when the window is closed so as to prevent any unauthorized entry from without, and which parts may be easily disengaged from each other at any time from within when it is desired to open 50 the window. The meeting edges of rails 1 and 2 are sometimes beveled as shown to make a tighter joint.

Secured to one of these sash rails, as 1 of the upper sash, is a stationary catch or hook device, consisting of an upright post

5 with an integral base 5^a secured to the rail 1 by screws 9, the upper part of the post 5 being formed in the shape of a hook with a horizontal part terminating in a depending lug 8 so that a recess 18 may be 60 provided between lug 8 and post 5, which recess 18 can be engaged by some other hooked or lug-provided member on the other sash. The post 5 is right-angled in cross-section or otherwise shaped to supply 65 a vertical wall 5^b (see Figure 3) at right angles to the rest of the post, and closing one end of slot or recess 18, so that the fastening device or hook that engages therewith may strike against wall 5^b when the 70 parts are in locking relation.

7 designates a fastening bar or rod, which may be round or square or any other shape and which is swiveled in a stationary base 6 that is secured to the other sash rail 2 75 by screws 10 so that said fastener may be moved about in a horizontal plane in convenient proximity to the stationary catch member on the other sash. This tubular bar or rod 7 has a vertical integral pin 19 80 thereon which is journaled loosely in a hole in the base 6, with a head to keep the pin in place, and on this loose pin the rod or bar 7 can be turned about, and moved back or forth in relation to the stationary 85 member 5. Also the bar or rod 7 has on one end a vertical lip or lug 17 which is calculated to enter slot 18 and engage behind the lug 8. One end of slot 18 is open so that the lug 17 can easily enter, but the 90 other end of slot 18 is closed by wall 5^b, and hence when the proper engagement has been made between lug 17 and the hooked end of the stationary catch device, said lug will strike against wall 5^b to keep it from 95 going too far and disengaging at the wrong time.

Thus the hooked stationary catch member and the hooked movable bar member may readily engage with each other and when so 100 engaged the two sashes of a window, or any other two parts that are related to each other similarly to the sashes of a window, will effectually be connected to each other, so that neither one can be moved until the 105 fastener is disengaged.

Of course this fastener is effective as described within certain limits, but in the case of a window that might be broken, or any door that might be cut, it might be possible 110

to gain access to the fastener and unfasten it. I aim to make this impossible, and I have provided fastening means for the purpose. The member 7 is provided with a passage or 5 is tubular, and therein is a locking rod 11, which has a terminal smaller screw-threaded section 12 that screws into a hole 16 in post 5, and it has also a screw-threaded section 14 near the other end that screws into a screw- 10 threaded interior part 21 of bar or rod 7, the end of rod 11 beyond threaded section 14 having a milled head 13 for turning the rod 11. This head has a shoulder that strikes the end of tubular rod 7, and has also a slot 20 15 for a screw driver or wrench, if needed.

After the movable tubular member 7 has been horizontally rotated to engage the hooked catch member, the said member 7 will have its longitudinal passage aligned 20 with the passage 16 in post 5, so that thereby turning the head 13 the screw-threaded rod 11 may be caused to engage the thread 21 and also the threads in passage 16, so that the engagement of lug 17 in slot 18 and 25 behind lug 8 will be very strongly effected and maintained and the parts cannot be separated without rotating the head 13 reversely so as to disconnect them.

Many changes in the precise details may 30 be made to adapt the invention for use in a great variety of places and of structures, such as windows, doors of various kinds, clo-

sures, shutters and the like, all within the scope of the ensuing claims.

What I claim, is:

1. In a device of the class described, the combination with a catch having a post provided with a lug to form a slot between the lug and post, of a pivoted movable hollow member having a lug adapted to enter said slot and engage the lug on the catch, and a fastening rod in the hollow member having a screw-threaded end that screws into an opening in the post portion of the catch and a second screw-threaded section that engages 45 into a threaded portion of the hollow member, said rod having a shouldered head for use in operating it.

2. In a device of the class described, the combination with a hook-shaped catch member, of a movable member provided with a passage through it and also a lug, which member has a headed downwardly projecting pin for swivelling, a base receiving the pin, and a fastening rod in the passage of the said member, said rod having a screw threaded section engaging a threaded opening in the catch member and a second screw threaded section engaging a threaded part of the passage in the aforesaid member, said 60 rod having a head for operating it.

In testimony whereof I hereunto affix my signature.

DENNIS JOSEPH GALLAGHER.
